E. E. BEARD

STEREOTYPE PLATE AND SUPPORT

Filed Jan. 5, 1923

Inventor

Elmer E. Beard

By *A. L. & S. L. Reynolds*

Attorneys

UNITED STATES PATENT OFFICE.

ELMER E. BEARD, OF PORT ANGELES, WASHINGTON.

STEREOTYPE PLATE AND SUPPORT.

Application filed January 5, 1923. Serial No. 610,932.

To all whom it may concern:

Be it known that I, ELMER E. BEARD, a citizen of the United States of America, and resident of the city of Port Angeles, in 5 Clallam County, State of Washington, have invented certain new and useful Improvements in Stereotype Plates and Supports, of which the following is a specification.

My invention relates to stereotype or electrotype plates such as are used in newspaper offices or printing offices for printing cuts and the like. Such plates are commonly made of thin material and are secured to a base-block, which raises them to the height 15 of ordinary type.

This invention relates to a method and means for securing the stereotype plate to the base block without the employment of special costly machinery and with a minimum of time.

It is also an object of my invention to provide securing means for such stereotype plates which may be cast in place as the plate itself is cast.

25 In this specification and in the claims I shall refer to the plate as a stereotype plate, although it may be made by any process and is not restricted in its use solely to plates made by the stereotype process. The invention is applicable to all two-part cuts or like matter which it is desired to build up to the proper type height.

30 My invention comprises those novel steps constituting the method and the novel constructions of the plate, base-block, and securing means which are illustrated in the accompanying drawings, described in the following specification and defined by the claims terminating the same.

40 In the accompanying drawings I have shown two possible securing means, both of which may be employed by the method which I shall proceed to describe.

Figure 1 is a transverse sectional view 45 through a built up stereotype plate and base-block, showing a means of attaching the plate to the block.

Figure 2 is an enlarged sectional view through a stereotype plate with one type of 50 securing means incorporated therein.

Figure 3 is a bottom plan view of the same.

Figure 4 is a perspective view of the preferred type of securing means separate

from the stereotype plate and before incorporation therein.

Figure 5 is a view similar to Figure 4 showing a slight modification.

It has been the practice in preparing stereotype plates for attachment to base 60 blocks to cast the plate with a rib or ribs depending therefrom and to form the base block with one or more undercut or dovetailed grooves to receive said ribs. This necessitated the installation and operation 65 of special machinery for undercutting or dovetailing the ribs to fit the groove in the base blocks, inasmuch as such dovetailed ribs could not conveniently be cast. Such machinery was expensive and its operation 70 required skill and time. Consequently it was not adapted for making cuts rapidly; cuts could not be inserted which came in near the time of closing the forms in a newspaper office. By my invention the ribs may 75 be formed to interlock with the grooves in the base-block by a very simple operation following the casting and one which requires no special tools or skill.

It should be understood that my invention is particularly intended for use in small shops where the best facilities are often not available. It is, therefore, essential that an inexpensive means and method be provided of quickly and easily casting a plate and for 80 attaching it to the base-block. I have shown the plate 1 as cast with a rib 10 integral therewith, the opposite sides of the rib being parallel and normal to the plate's back, or slightly inclined, in order that they may be 85 cast easily in a mold and removed therefrom. In order to secure the plate upon the base-block 4 I provide means which are secured in the ribs 10, or incorporated therein when cast, which can thereafter be formed to interlockingly engage the undercut side or sides 41 of the groove or grooves 40 in the base-block. Such means are usually adapted to be engaged with the under-cut sides 90 41 by relative sliding movement of the plate 100 and block 4, and cannot be disengaged by movement of the plate and base-block in a direction normal with their faces.

The means for securing the plate in place in the groove 40 of the base-block I have 105 shown as consisting of small channels comprising two parallel sides 2 and a connecting web 21. These are cast into the rib by in-

serting them into the groove of a casting mold, and by then pouring the metal to form the rib and cut plate between the faces 2 and behind the web 21, thus forming a composite 5 plate and rib such as is shown in Figures 1, 2 and 3. The side faces or flanges 2 of the channel may define the outside faces of the rib, and the web 21 lies either in the rib 10 or in the plate 1. The metal of the plate 10 and of the rib will adhere or weld to the metal of the channel so that a strong and permanent joint is formed. After the metal of the plate has cooled sufficiently, the faces 2 of the channel are pressed or projected 15 outwardly, as with a screw driver or other pointed tool, to form lugs 22 in the sides of the rib. It will be understood that the channel is formed of pliable material. These lugs 22 project outwardly of the general plane of both side faces of the rib and will ordinarily extend farthest at that edge of the rib which is farthest from the base of the rib 10, that is, farthest from the back of the plate 1. These lugs will engage beneath the undercut faces 41 of the plate 1 groove and will secure together the plate 1 and base plate 4. If desired, the lugs 22 may be projected from a single face 2 only.

It is my intention to provide slits 23 in 30 the web 21 at intervals to permit the stereotype metal to flow therethrough and to join the metal of the rib and plate through these slits. This, while desirable, is not essential and in the modification shown in Figure 5 35 has been omitted.

The cut form thus made up is light in construction, is of the proper height, the amount of metal consumed in making the cut is not large, and the cut itself is small 40 so that it may be conveniently stored. The entire operation, once the mold is heated, requires but very little time, and cuts may be run even though the mats from which they are made arrive but a short time prior 45 to closing the forms. Obviously many variations in the form and character of these groove-engaging members may be evolved, and I do not desire to limit myself to the particular members described. Neither do 50 I desire to be limited to any apparatus for practising the method disclosed, nor to any succession of steps in the method. Those features which constitute my invention are set forth in the following claims.

55 In carrying out my invention the backing block is not changed and the printing plate is changed only by incorporating therein the pliable metal strip or strips which after being bent laterally or away from the rib 60 form members which cooperate with the undercut or dovetail groove or channel of the backing block to lock block and plate together.

It is evident that the invention lies mainly 65 in the use of a strip of pliable metal adapt-

ed to be secured to project from the plate when the plate is cast and then to have its projecting portion laterally bent so that it may serve as the means for fixing plate and block together.

It is also evident that the chief element of commercial sale is the pliable metal strips ready for use in making the printing plates.

The characteristic feature of my invention is casting or molding into the rib of a 75 plate of a member capable of being manually deformed or modified in shape or position after casting so as to be thereby interlocked with an undercut groove in the base and thereby lock the two together.

What I claim as my invention is:

1. A printing plate having a rib projecting from its back face and a pliable member lying in a side face of the rib and secured along the base of the rib and adapted to be 85 bent outwardly from the rib to constitute a member adapted to interlock with an undercut groove in a base block.

2. A printing plate having a rib projecting from its back face and having incorporated therein by casting a securing member adapted to be bent outwardly from the side face of the rib to thereby form a dovetail member adapted to cooperate with an undercut channel in a backing block to secure the 95 two together.

3. A means for securing a printing plate to a backing block comprising a pliable metal strip adapted to be secured to the plate by partial imbedding therein when the plate is 100 cast so as to have an edge projecting, said edge being adapted to be bent after casting to interlockingly engage the undercut edge of a channel in the face of the backing block.

4. A cast printing plate having pliable 105 metal elements partially imbedded therein at casting, the projecting parts of said elements being bendable to enable them to interlockingly engage the undercut face of a groove in the backing block.

5. A stereotype plate and a base-block therefor, the plate having a rib including a pliable channel element integral therewith, said channel being extended laterally at intervals beyond the general plane of the rib's 115 side face, and the base-block having a groove of substantially the same width as the rib, and undercut to receive the said channel extensions.

6. In a stereotype cut form, the combination with a cast plate and a parallel-sided rib integral therewith, of projections secured in said rib and extending laterally of the rib, and a base-block for said plate having a rib-receiving trough, said trough being undercut 125 to receive said projections.

7. A stereotype plate having a rib cast integral therewith, and a plurality of members secured in said rib and projecting from a side thereof.

8. A stereotype plate having a rib cast integral therewith, and a plurality of members secured in said rib and projecting from a side thereof above the bottom edge of the 5 rib.
9. A stereotype plate having a rib cast integral therewith, the side faces of said rib as cast including and being defined by a pair of parallel plates of pliable material, said 10 pliable plates being later extended at intervals outwardly of their original plane.
10. A stereotype plate having a rib cast integral therewith, said rib including a channel of pliable material defining its sides 15 at the edge distant from the plate, the sides of said channel being later projected laterally at intervals beyond its original plane.
11. A pliable metal strip of a parallel-
- sided channel cross section adapted to have its base imbedded in a cast printing plate 20 with its wings projecting, whereby by bending outwardly the projecting wings a dovetail member is formed adapted to interlock the plate with a base block.
12. As an article of manufacture a strip 25 of pliable metal adapted to be secured to project from the back of a printing plate by casting therein and by lateral bending after casting to form a member adapted to interlock with a backing block to secure the plate 30 thereto.

Signed at Port Angeles, Clallam County, Washington this 15th day of December, 1922.

ELMER E. BEARD.
